UNITED STATES PATENT OFFICE

2,250,678

MACHINE FOR MOUNTING SHOES ON LASTS

Edward Quinn, Malden, Mass., assignor to The
Del-Mac Shoe Process Corporation, New York,
N. Y., a corporation of New York

Application March 28, 1939, Serial No. 264,598

12 Claims. (Cl. 12—15)

This invention relates to machines for mounting shoes on lasts and is herein illustrated and described as embodied in a machine suitable for operation upon shoes of the type disclosed in United States Letters Patent No. 2,107,502, granted February 8, 1938, upon my application. While the shoes disclosed in said Letters Patent are assembled off the last, the present invention is also applicable to the relasting of turn or McKay type shoes. In either case the practice 10 of the invention is of particular advantage in cases wherein the operation must be performed without unduly straining the shoe.

Previous relasting machines, for example, machines of the type disclosed in United States Letters Patent No. 1,856,291, granted May 3, 1932, on the application of Arthur F. Pym, are intended to operate upon one-piece lasts. However, wherever strain must be particularly avoided it is desirable to employ hinged or separable lasts. Machines of the type disclosed in the above-mentioned Letters Patent to Pym can operate to advantage upon such lasts only if some provision is made to prevent the last, when straightened, from being broken again by the pressure which these machines apply to the shoe bottom.

An object of the invention is to provide an improved machine for mounting shoes on lasts. In accordance with this object a feature of the invention comprises an automatic means for operating a shoe horn to seat the heel end of a shoe upon a last, and means controlled directly by the operator for causing the horn to perform a relasting operation upon the heel end of the shoe in advance of the operation of the automatic means. After the operation of the horn a power driven roll may be applied to the bottom of the forepart of the shoe to urge the shoe rearwardly on the last and thereby take up looseness in the toe portion. As illustrated herein the improved machine is provided with a locking member in the form of a wedge which engages both the forward and rear sections of the last to hold the last in straightened condition.

Other objects and features of the invention will be apparent from the following description, reference being had to the accompanying drawings, in which

Fig. 1 is a vertical sectional view of the improved machine;

Fig. 2 is a vertical sectional view of a portion of the interior mechanism of the machine;

Fig. 3 is a sectional view in a plane taken on the line III—III of Fig. 1;

Fig. 4 is a vertical sectional view of the mechanism for holding the last pin;

Fig. 5 is a side elevation of a portion of the mechanism shown in Fig. 4;

Fig. 6 is a view in vertical section taken on the line VI—VI of Fig. 1; and

Figs. 7 to 14, inclusive, are views illustrating consecutive stages in the operation of mounting a shoe upon a last.

In the drawings, L designates a last and S designates a shoe which is being mounted on the last. The last herein illustrated is of the two-part hinged type and is shown as mounted upon a last pin P with which the machine is provided. A shoe horn H interposed between the shoe and the last rocks about the heel end of the last to draw the counter portion of the shoe over the last and a rubber roll R rotates against the bottom of the forepart of the shoe to urge the shoe rearwardly upon the last. The roll R and horn H are arranged to be operated in timed relation to each other by a power-driven cyclically controlled mechanism. Provision is made, however, for enabling the operator to control the rotation of the roll R independently of the cyclic mechanism and also to operate the horn H directly through a foot treadle before initiating the operation of the power-driven mechanism which then serves to continue the movements of the horn and eventually to return the various parts to their initial positions.

The supporting structure of the machine comprises a housing 20 which encloses the greater part of the mechanism for operating the roll R and the horn H and which has an upward gooseneck extension 22 which carries the last pin P.

The last pin P (Figs. 1 and 4) is secured in a carrier 24 which is pivotally mounted upon a pin 25 secured in a downward extension 26 of the gooseneck 22. The last pin is normally held up at an angle slightly above the horizontal, as shown in Fig. 7, by a spring 28 housed in a bore formed in the downward extension 26 and acting upon a rod 30 connected to the carrier 24 through a link 32. The carrier has formed in its upper portion a notch 34 engageable with the lower end of a plunger 36 to latch the carrier in the position shown in Fig. 8 wherein the last pin extends downwardly. The plunger is normally held down by a spring 38 and may be raised by hand through a finger 40 and may also be raised automatically, as will later be described, through a finger 42. The mounting of the last pin P and the provisions above described for latching it in its operative position

are substantially like the corresponding arrangements in the above-mentioned Letters Patent No. 1,856,291. A spring metal plate 43, secured at its upper end to the gooseneck, extends downwardly for a purpose which will later be explained.

Provision is made for rigidly maintaining the last L in open position after it has been straightened within the shoe S. The means for doing this comprises a wedge-shaped block 44 shaped to enter the space between the two sections of the last when the last is open to hold the last positively against "breaking." The block 44 is channel shaped in cross section, consisting of a pair of parallel walls connected by a bridge 45. Formed on the outer surface of the bridge 45 are serrations 46. Similar serrations 48 are formed on the rear edges of the walls of the block. These serrations frictionally engage the adjacent surfaces of the two sections of the last to prevent the block from being forced out. The block 44 is pivotally mounted upon the lower end of a depending link 48 which extends into the space between the walls of the block, the upper end of the link 48 being pivotally mounted upon a slide 50. A bracket 52 secured upon the gooseneck 22 carries a vertical channel shaped guideway 54 for the slide 50. The bracket 52 has a central relatively narrow open-ended slot, the upper end of which is indicated by the reference character 53, to accommodate the link 48. The guideway 54, which bridges this slot, is secured to the bracket 52 by four screws 55. A spring pressed latch 56 (Fig. 5) pivotally mounted in the guideway 54 engages a notch in the slide 50 and thus normally holds the slide in an upper or inoperative position. A block 57 secured to the slide 50 prevents the slide from dropping out of its guideway when the latch is disengaged. The slide is provided with a hook 58 to facilitate its being raised by the operator to its inoperative position.

The power by which the machine is driven is transmitted from any convenient source through a chain 62 (Fig. 2) to a continuously rotating shaft 64 journaled in bearings carried by the housing 20. A worm 66 which is freely rotatable upon but is held against endwise movement with respect to the shaft 24 engages a worm wheel 68 fixed upon a cam shaft 70 also journaled in bearings carried by the housing 20. A worm wheel 71 rotating in a housing containing lubricant engages the worm 66 for purposes of lubrication. The worm 66 may be driven through a clutch mechanism comprising a clutch member 72 fixed upon the shaft 64 and a clutch member 74 frictionally engageable with the member 72 and free to slide and rotate upon the shaft 64. The loose clutch member 74 is urged into engaging position by springs 76 and drives the worm 66 through a tongue and slot connection. The clutch member 74 is normally held out of engagement by a bell crank lever having an arm 78 which carries a pair of pins engageable with an annular groove in the hub of the clutch member. The above-mentioned bell crank has a second arm 80 which carries a tripping lever 82 normally held down by a clutch control lever 84 which is connected through a link 86 to a lever 88 carrying a cam roll 90. A cam 92 on the shaft 70 engages the roll 90. A starting treadle 94 operates through a link 95 to trip the lever 82 and thereby release the clutch member 74 from control of the lever 84, whereupon the springs 76 urge the clutch member 74 into engaging position. The treadle 94 is normally held up against the end of a slot

in the frame 20 by a spring 93. The worm 66 thereupon begins to rotate and drives the shaft 70 through the worm wheel 68. It will be observed that the cam 92 has three rises, each of which 5 may hold the cam roll 90 in a position to hold the lever 84 down. As soon as the cam 92 begins to rotate, the lever 88 is enabled to swing in a clockwise direction, thereby enabling the lever 84 to rise. When the treadle 94 has been released 10 the lever 84 will thus be raised high enough to enable the tripping lever 82 to come into a position wherein an ear on the tripping lever is directly under a lug on the control lever 84. Further rotation of the cam 92 will cause the next 15 rise of the cam to depress the control lever 84 thereby rotating the bell crank 78, 80 in a counterclockwise direction to disengage the clutch, thereby stopping the rotation of the cam shaft 70. A stationary brake band carried by a bracket 91 20 engages the clutch member 74 as soon as the latter has moved away from the clutch member 72. The clutch mechanism above described is substantially like that disclosed in the above-mentioned Letters Patent No. 1,856,291. It is thus 25 evident that each cycle of operations is initiated by depressing the treadle 94 and terminates automatically upon rotation of the cam shaft through a predetermined angle.

In order to enable the roll R to be raised from an inoperative position into engagement with the bottom of the forepart of the shoe S there is provided a bracket 96 which is pivotally mounted for swinging movement about a stationary shaft 98 fixed in the upper portion of the housing 20. The roll R is carried upon a shaft 100 which is journaled in bearings carried by a slide 102 on the bracket 96, the slide being movable for adjustment toward and from the shaft 98. Such adjustment of the slide 102 is effected through a shaft 104 journaled in the upper portion of the housing 20 and having a hand wheel 106 by which it may be turned. Secured upon the shaft 104 is a worm 108 which engages a worm wheel 110 freely rotatable upon the shaft 98. Secured to 30 the hub of the worm wheel 110 is a gear 112 which meshes with rack teeth 114 formed in the upper edge of a bar 120. The bar 120 is slidably mounted in the bracket 96 and has on its lower edge rack teeth which engage a pinion freely rotatable upon a shaft 122 mounted in the carriage 120. A second pinion fixed to the hub of the first engages rack teeth formed on the under surface of the slide 102 to move the slide relatively to the bracket 96. The above-described mounting 35 of the roll R and the provision for its adjustment are similar to the corresponding arrangements disclosed in the above-mentioned Letters Patent No. 1,856,291.

To provide for raising and lowering the roll R, 40 a rod 124 is pivotally connected at its upper end to the bracket 96. The lower end of the rod 124 is freely slidably through a sleeve 126 which is trunnioned upon the end of a lever 128. It will be observed that the lower portion of the 45 rod 124 is within the housing 20, while the upper portion passes through an opening 130 formed in the housing 20. A sleeve 132 is slidably mounted upon the rod 124 at a considerable distance above the sleeve 126. Securely fixed in the sleeve 132 and extending diametrically thereacross is a pin 134 which engages the lower end of a rod 138 threaded axially through the upper portion of the rod 124. A compression spring 140 surrounding the rod 124 is interposed between the sleeves 132 and 126, urging the sleeve

132 upwardly as far as permitted by the engagement of the pin 134 with the rod 138. A collar 142 secured upon the lower end of the rod 124 engages the lower edge of the sleeve 126 and thus retains the rod 124 within the sleeve. Adjustment of the compression of the spring 140 is effected through a hand wheel 144 carried by the rod 138. In order to provide for adjustment of the bracket 96 relatively to the rod 138 the rod is not connected directly to the bracket but is threaded through a sleeve 146 which, in turn, is pivotally connected to the bracket. The lever 128 is fulcrumed upon a fixed shaft 148 secured in the lower portion of the housing 20. Secured in fixed relation to the lever 128 for swinging movement about the fulcrum 148 is an arm 150. A cam roll 152 carried by the arm 150 engages a rotary cam 154 securely fixed upon the shaft 70. It will be evident that rotation of the cam 154 will rock the lever 128 to transmit a thrust through the spring 140 and thence through the upper portion of the rod 124 to swing the bracket 96 upwardly about its fulcrum 98. The above-described construction for raising the roll R is similar to the corresponding arrangements disclosed in United States Letters Patent No. 1,930,487, granted October 17, 1933, upon the application of Harold S. Pym et al.

Rotation of the roll R is effected through mechanism comprising beveled gearing 156 driven by a shaft 158 journaled in the carriage 102. The lower end of the shaft 158 is connected through a universal joint to an extensible telescoping shaft 160 the lower end of which, in turn, is connected through a universal joint to a vertical shaft 162 journaled in bearings carried by the housing 120. Upon the lower portion of the shaft 162 is secured a worm wheel 164 which engages a worm 166 mounted for free rotation upon the continuously driven shaft 64. The worm 166 is driven through a friction clutch 168 which is operated through a lever 170 fulcrumed upon a pin 171 carried by a stationary bracket within the housing 20. Extending from the lever 170 is a forked arm 172, the two branches of which are pivotally connected to the lower ends of a pair of parallel links 174, one of the links being visible in Fig. 2. The upper ends of the links 174 are pivotally connected to a sleeve 176 surrounding a vertical rod 178. The rod 178 is freely slideable and rotatable in bearings 180 carried by the housing 20, and may turn freely within the sleeve 176. A pair of collars 182 and 184 secured to the rod 178 in abutting relation to the respective ends of the sleeve 176 cause the sleeve to partake of the vertical movements of the rod. Threaded upon the rod 178 below the collar 184 is a nut 186. Slidably mounted on the rod 178 some distance below the nut 186 is a block 188. A collar 190 secured to the rod 178 below the block 188 limits the downward movement of the block relatively to the collar. A compression spring 192 surrounding the rod 178 and interposed between the nut 186 and the block 188 normally holds the block down against the collar 190. The rod 178 is free to turn within the block 188, the block, however, being held against turning by a guide post 194 upon which it is freely slideable. The compression of the spring 192 may be adjusted by turning the rod 178 within the nut 186, the upper end of the rod being squared, as indicated by the reference numeral 196 to facilitate turning. The nut 186 has a squared portion which slidably engages two guide lugs 200 on the inner wall of

the housing 20 to keep the nut from turning. A pair of studs 202 are provided to prevent the nut 186 from being disengaged from the threads on the rod 194. These studs are threaded into the nut 186 on opposite sides of the rod 178 and have smooth shanks which slidably engage openings in a plate 204 which surrounds the collar 184 and rests upon a flange formed on the lower portion of the collar, the studs having heads which cannot pass through the openings in the plate 204.

Raising of the rod 178 to engage the friction clutch 168 may be effected through two separate instrumentalities, one of which is automatic and the other of which is operated by a treadle. The connections to the separate operating instrumentalities comprise a pair of parallel rack bars 206 (one of which appears in Fig. 2) slidably mounted in the block 188 and simultaneously engaging in diametrically opposed relation a pinion (not shown) mounted for free rotation on the block 188. This arrangement enables either rack bar to be raised even if the other is stationary, in which case the pinion will roll up on the stationary rack bar and raise the block 188, thus transmitting a yielding thrust through the spring 192 into the rod 178. One of the rack bars is connected by a link 208 to one arm of a lever 210 fulcrumed upon a stationary shaft 212. The lever 210 has another arm carrying a roll 214 which engages a cam 216 secured upon the shaft 70. A spring 218 normally holds the roll in engagement with its cam. Rotation of the cam shaft 70 will thus cause the friction clutch 168 to engage automatically at a predetermined point in the cycle of operations. The other rack bar is connected through a similar link to a treadle 220 by which the operator can engage the friction clutch 168 at will. The treadle 220 is normally held up against the end of a slot in the frame 20 by a spring 219. The above-described mechanism for rotating the roll R and for controlling the rotation thereof is substantially like corresponding mechanism disclosed in the above-mentioned Letters Patent No. 1,856,291. Attention is directed particularly to Fig. 13 of said Letters Patent for a showing of a similar arrangement of a pinion and two operating racks.

The horn H is pivotally mounted for swinging movement upon a pin 221 carried by a bracket 230 mounted upon the upper end of a tubular rod 224. The lower portion of the rod 192 is in telescopic engagement with a rod 226 the lower end of which is fulcrumed upon a stationary shaft 228 secured in the lower portion of the housing 20. A tension spring 222 having its lower end anchored within the rod 224 and its upper end secured to a tail 232 extending from the horn H yieldably urges the horn upwardly about the pin 221 to a stop position. The movements of the horn H are derived from two components one of which is represented by the sliding movement of the tubular rod 224 on the rod 226 and the other of which is represented by the rocking of the arm 226 about its fulcrum pin 228. The tubular rod 224 may be raised on the rod 226 by mechanism comprising a lever 234 (Figs. 1, 3 and 6) fulcrumed at one end upon a stationary shaft 236 and having a forked opposite end to which are pivotally connected two parallel depending links 238 on opposite sides of the rod 224. The lower ends of the links 238 are pivotally connected to a sleeve 240 adjustably clamped upon the rod 224. The intermediate portion of the lever 234 carries a roll 242 which engages a cam 244

secured upon the shaft 10. A spring 245 normally holds the roll 242 against the cam 244. It is evident that rotation of the cam 244 will operate to raise the rod 224 and to enable it to descend. To enable the rod 226 to be rocked about the fulcrum 228 there is provided a longitudinal slot 245 (Fig. 6) in the tubular rod 224 through which extends an ear 246 secured to the rod 226. Pivotal connected to the ear 246 is one end of a link 248 the opposite end of which is pivotally connected to a sleeve 250 which, in turn, is adjustably mounted on a sleeve 251 carried upon a rod 252 (Fig. 6). Collars secured to the rod 252 at the ends of the sleeve 251 hold the sleeve against axial movement relatively to the rod while enabling the rod to turn freely within the sleeve. Movement of the rod 252 to the left, as viewed in Fig. 1, is accomplished through a link 254 pivotally connected at one end to a sleeve 256 and at its other end to one arm of a lever 258 fulcrumed upon the pin 236. The other arm of the lever 258 carries a roll 260 which engages a cam 262 mounted upon the shaft 10. A spring 263 normally holds the roll 260 on the cam 262. Threaded upon an end portion of the rod 252 is a nut 264 which slidably engages the interior of a bearing 226 carried by the housing 20. The nut 264 is keyed to the bearing to prevent turning. Surrounding the rod 252 and interposed between the sleeves 256 and the nut 264 is a compression spring 268 which yieldingly transmits the thrust of the sleeve 256 into the rod 252. A collar abutting the sleeve 251 holds the sleeve 256 against the thrust of the spring 268. The rod 252 is keyed to a spiral gear 270 the hub portion of which is mounted in a bearing 272 carried by the housing 20. A collar 273 secured to the hub of the gear 270 engages an annular slot in the bearing 272 to hold the gear against endwise movement. A gear 274 engaging the gear 270 may be turned by a hand wheel 276 to cause rotation of the rod 252 in the nut 264, thus varying the compression of the spring 268. The horn H above mentioned and also the mechanism as so far described for operating it are similar to corresponding mechanism described in the above-mentioned Letters Patent No. 1,856,291.

As has already been mentioned, the horn H may be operated directly by a treadle as well as by the automatic mechanism, the two components of movement being imparted to the horn by mechanism which will now be described. Extending from one of the links 238 is a lug 278 through which passes a cable 280. One end of the cable 280 is secured to a block 282 below the lug 278. A spring 284 anchored at its lower end to a portion of the housing 20 and secured at its upper end to the block 282 exerts a downward tension upon the cable. The cable passes upwardly through the lug 278 past a guide pulley 286 mounted on a stud which pivotally connects the adjacent link 238 to the lever 234 and thence upwardly around a pulley 288 and thence downwardly outside of the housing 20 to a slide 289 (Fig. 3) to which is secured a treadle 290. For convenience the wall of the frame for this locality consists of a door 292 hinged on pintels 294 (Fig. 6) carried by the housing 20. The door 293 may be held shut by a hook 295 engaging the inner wall of the housing 20. The hook 295 has a round shank which may be turned from the outside to disengage it. The portion of the treadle extending within the guideway is retained therein by gibs 296. It is evident that depre-

sion of the treadle 290 will cause the cable 280 to lift the block 282 against the tension of the spring 284 into contact with the under surface of the lug 278 to raise the link 238 and thereby 5 move the tubular rod 224. In order to obtain the properly related component of swinging movement about the fulcrum 228 there is provided a wedge-shaped cam 298 having an inclined surface engageable with a roll 300. Pivotal mounted 10 upon the studs which connect the links 238 to the lever 234 is a yoke 302 in which is secured a stud 304 upon which the roll 300 is freely rotatable. A bearing member 306 carried by the yoke 302 engages the tubular rod 224. As the treadle 15 290 is depressed to raise the horn H the yoke 302 will also be raised, causing the roll 300 to travel up along the inner surface of the door 292 and then up the inclined surface of the cam 298, thereby rocking the rod 224 in a counterclockwise 20 direction as viewed in Fig. 1. A tension spring 308 interposed between the yoke 302 and the sleeve 240 holds the cam roll 300 against the surface of the door or against the cam 298 during the upward movement of the roll. The cam 298 25 is pivotally mounted at its upper or thick end upon a stud 310 carried upon a slide 312 which extends through a slot 313 formed in the door 292. The slide 312 is adjustable in and out, or to the right and left, as seen in Fig. 1, being slidable 30 in a guideway formed in a second slide 314, which, in turn, is slidable for purposes of adjustment in a vertical guideway 315 formed on the outside of the door 292. The lower or thin end of the cam 298 rests against the inner surface 35 of the door 292. The door 292 above the thin edge of the cam 298 is bulged outwardly, as indicated by the reference numeral 316. As soon as the roll 300 in its upward travel passes the upper end of the cam 298 the spring 308 causes 40 it to move to the right, as viewed in Fig. 1, until it engages the inner surface of the bulged portion 316 of the wall. The cam in its descent may now pass between the inner surface of the wall and the cam 298, the inner wall of the door sloping gradually as the roll descends to enable the roll to push the cam 298 to the left out of its way until it is past the thin end of the cam, whereupon a spring 318 draws the cam to the right 45 until the thin end again rests against the unbulged portion of the door 292. The operation of mounting the shoe S upon the hinged last L by the use of the machine disclosed herein will now be described. The toe end of the last is loosely inserted into the shoe while the 50 last is in broken condition and the last is then mounted upon the last pin P while the latter occupies its uppermost or out-of-the-way position. If desired, the last may be mounted upon the last pin before the shoe is loosely mounted upon the toe end of the last. Referring to Fig. 7, it will be 55 observed that the toe end of the shoe is inclined somewhat from the vertical to enable it to clear the slide 50 and the guideway 54. The roll R and the horn H will occupy their normal or lowermost positions, as shown in Fig. 1. The operator then 60 swings the shoe and last downwardly about the pin 25 to the position indicated in Fig. 8, turning the last about the last pin to bring the heel end of the last into alignment with the horn H. The 65 horn H is raised by depression of the treadle 290 to such a height as to cause the heel end of the last in its downward swinging movement to engage the horn tangentially, the spring 222 permitting the horn to yield slightly. When the last pin has reached its lowermost position the lower 70 75

end of the rod 36 will snap into the recess 34 to lock the last pin in operating position. The horn H, as shown in Fig. 8, will now press against the bottom of the heel end of the last. The extent to which the horn overlaps the last bottom depends largely upon the adjustment of the sleeve 250 along the sleeve 251 and upon the adjustment of the slide 312 in its guideway. The most desirable heightwise position of the last for the fulcruming of the horn about the heel end of the last may be determined by a stop nut 23 threaded on the last pin and engageable with the cone of the last. The operator now further depresses the treadle 290, causing the horn carrier 230 to rise and rock about the heel end of the last bottom until the horn begins to engage the interior of the shoe upper. The operator will now feel the resistance of the shoe through the treadle and will govern the pressure he is exerting through the treadle accordingly. While the operator is thus actuating the horn through the treadle he will press downwardly upon the toe portion of the shoe with his right hand, as indicated in Fig. 9, guiding the heel end of the shoe upwardly with his left hand. The downward pressure of his hand, together with the force exerted by the horn, will cause the broken last to straighten. The operator is enabled to coordinate the work done by the horn H with that done by his hands, applying greater or less force wherever required as the operation progresses. After the last has been straightened he depresses the treadle 290 until it touches the floor, and holds it there. Such operation of the horn through the treadle 290 will cause the rolls 242 and 260 to be raised from the cams 244 and 262 respectively. The last and shoe will then occupy the position indicated in Fig. 10 with the heel end of the shoe partly drawn over the last and with the horn, using the last as a fulcrum, exerting a rearward pull upon the heel end of the shoe upper. The operator can now observe if the shoe is properly alined relatively to the last and if twisted he will straighten it by hand.

Although the shoe is now partially mounted upon the last there is still some looseness between the toe portion of the shoe and the last. It is undesirable to rely upon tension alone to draw the shoe rearwardly upon the last to take up this looseness because of the danger of unduly stretching or otherwise damaging the shoe. The operator now trips the latch 56, enabling the wedge block 44 to drop down into the space between the forward and rear sections of the last L. The block 44, by reason of its pivotal connection to the link 48 and by reason of the link 48 being pivotally connected to the slide 50, will automatically find its way into the space between the sections of the last. The serrations 46 and 48 now hold the last securely in straightened condition. The operator then depresses the starting treadle 94 to initiate the first cycle of operation of the machine. The automatic operation of the machine brings the roll R up against the bottom of the forepart of the shoe with considerable pressure and the roll rotates against the shoe bottom to urge the shoe rearwardly on the last and the first cycle of operation automatically ends. After the termination of the first cycle the operator again makes sure that the shoe is not twisted in relation to the last, and he may tap the toe portion of the shoe or manipulate it in such manner as may be required. The operator may then depress the treadle 220 to cause further rotation of the roll R if called for.

In many cases however it is desirable to dis-

pense with the automatic rotation of the roll R, which may be done by simply removing the cam roll 214 together with the stud upon which it rotates. The roll R can now be rotated only by depressing the treadle 220, which operates by causing the link 208 attached to the treadle rod (Fig. 2) to exert a direct thrust against the under surface of the block 188. The first cycle of automatic operation will now merely bring the roll R into operating position without rotating it. After the termination of the first cycle the operator causes the roll R to be rotated under his direct control, the degree of pressure which he exerts upon the treadle 220 determining the amount of force which can be transmitted through the roll R before the clutch 168 slips. The shoe is thus urged rearwardly on the last to take up all looseness at the toe portion. No movement of the horn takes place at this time except, perhaps, a slight yielding movement as the longitudinal tension in the shoe slackens.

The second cycle of operations is initiated by again depressing the starting treadle 94. Rotation of the cams 244 and 262 eventually will bring their raised portions into engagement with their respective rolls, and thus cause the horn H to be controlled by the rotary cams. In the course of this cycle the horn H is raised automatically from the position shown in Fig. 11 to that shown in Fig. 12, drawing the heel end of the shoe completely upon the last. During the latter stages of this cycle the roll is retracted from the shoe bottom. The horn in its upward movement is withdrawn from between the shoe and last and as it continues upwardly it engages the finger 42 and raises the latch rod 36, enabling the spring 28 to swing the shoe upwardly toward out-of-the-way position. In Fig. 4 the shank of the horn H and the pin 221 are shown in broken lines at their uppermost positions. The spring metal plate 43 serves as a guide for these parts as they move upwardly. The second cycle now terminates, and the operator now removes the last and shoe from the last pin and from the wedge block 44 which readily disengages as the shoe and last are withdrawn.

The starting treadle is depressed once more to initiate the third and last cycle of operation, wherein all the machine parts are automatically returned to their initial positions, with the exception of the wedge block 44 which is raised manually.

In mounting the next shoe upon its last the operator, if he so desires, can keep his foot on the special horn treadle 290 before initiating the last cycle. By reason of the direct control which the special horn treadle gives him he can let the horn down to a position suitable for engagement with the heel end of the last while the last is swinging down into operating position.

It may be observed that the improvements of the machine described herein do not in any way prevent the machine from being used for operations upon one-piece lasts in the manner of the machine disclosed in the above-mentioned Letters Patent No. 1,856,291 if it is desired to do so. The illustrated machine can also be used with lasts of the self-locking type. In such cases the wedge block 44 will not be used.

Having thus described my invention, what I claim as new and desire to secure by Letters Patent of the United States is:

1. In a machine for mounting shoes on lasts, a shoe horn, automatic means for operating said horn to seat the heel end of a shoe upon a last,

and means directly controlled by the operator for causing said horn to perform a relasting operation upon the heel end of the shoe in advance of the operation of said automatic means.

2. A machine for mounting shoes on lasts, comprising a support for a last with a shoe loosely mounted thereon, a horn, power operated means for rocking said horn about the heel end of the last to draw the shoe on the last and for withdrawing the horn from between the shoe and the last, and treadle operated means for effecting said movements of the horn independently of and in place of said power operated means to enable the operator to move the horn under direct control before starting said power operated means.

3. A machine for mounting shoes on lasts, comprising a support for a last with a shoe loosely mounted thereon, a horn, a carrier upon which said horn is yieldingly mounted for rocking movement, a pair of driven rotary cams, mechanism operated by said cams for causing said carrier to move the horn to draw the shoe over the heel end of the last, one of said cams serving to impart to said carrier a heightwise component of movement and the other cam serving to impart a lengthwise component relatively to the last, treadle operated means for raising the carrier independently of said cams, and a stationary cam for imparting to said carrier a component of movement lengthwise of the shoe as the carrier is raised by the treadle to enable the horn to perform an operative movement under direct control of the operator before causing the horn to be moved by said rotary cams.

4. In a machine for mounting shoes on lasts, a support for a last, a shoe horn, a carrier for said shoe horn, a lever on which said carrier is mounted for longitudinal movement with respect thereto, a fulcrum for said lever, means for moving said carrier along said lever to impart an operative movement to said shoe horn whereby the counter portion of a shoe loosely mounted on the last is drawn over the heel end of the last, a stationary cam, and means including a member engageable with said cam and movable with said carrier for swinging said carrier about said fulcrum to control the direction of the operative movement of the horn to best advantage.

5. In a machine for mounting shoes on lasts, a support for a last, a shoe horn, a carrier for said shoe horn, a lever on which said carrier is telescopically mounted for free longitudinal movement, a fulcrum for said lever, means for moving said carrier along said lever to impart an operative movement to said shoe horn whereby the counter portion of a shoe loosely mounted on the last is drawn over the heel end of the last, a stationary cam, a roll engageable with said cam and movable with said carrier arranged to swing said carrier about said fulcrum to control the direction of the operative movement of the horn to best advantage, and yieldable means for urging said lever in a direction to hold said roll against said cam.

6. In a machine for mounting shoes on lasts, a support for a last, a shoe horn, a carrier for said horn, a lever on which said carrier is telescopically mounted for longitudinal movement, a fulcrum for said lever, a treadle, a cable connecting said treadle with said carrier, guide means for said cable constructed and arranged to cause the cable to raise said carrier upon depression of said treadle, the raising of said carrier serving to move the horn operatively to draw over

the heel end of the last the counter portion of a shoe loosely mounted on the last, a roll engageable with said cam and movable with said carrier arranged to swing said carrier about said fulcrum to control the direction of the operative movement of the horn to best advantage, and a spring acting on said lever to urge the roll against the cam.

7. A machine for mounting shoes on lasts comprising a support for a last with a shoe loosely mounted thereon, a roll constructed and arranged to seat the forepart of the shoe on the last, a horn for seating the rear part of the shoe on the last, cyclically operating mechanism constructed and arranged to cause the roll and the horn to seat the shoe on the last, and a treadle mechanism for enabling the operator to operate the horn under direct control independently of and in place of said cyclically operating mechanism.

20 8. In a relasting machine, a support for one section of a hinged last, a member constructed and arranged to engage both sections of the last when the last is in a straightened condition to prevent breaking of the last, and a support for 25 said member constructed and arranged for movement of the member between operative and out-of-the-way positions.

9. In a relasting machine, a last pin for supporting the heel section of a hinged last, a member 30 constructed and arranged to enter the space between the two sections of the last to maintain the last in straightened condition, a vertical guideway, a slide in said guideway, a link depending from said slide, said member being pivotally mounted on said slide, and a latch for holding said slide up in an out-of-the-way position, said guideway being arranged to enable the slide when unlatched to drop into a position wherein said member enters the space between the two sections of a straightened last on said last pin.

10. A machine for use in mounting shoes on lasts comprising a support for a two-part last, means for urging a shoe partially upon the last 45 before the last has been completely straightened, means for holding the last in straightened condition, and means for urging the shoe further upon the last while the last is held straightened by said holding means.

11. A machine for use in mounting shoes on lasts comprising means for supporting a two-part last in broken condition with the forepart of a shoe loosely mounted on the forepart of the last, means for assisting the operator to 55 straighten the last and for drawing the heel portion of the shoe over the heel portion of the last, means for holding the last in straightened condition, and means for urging the shoe rearwardly upon the straightened last.

12. A machine for use in mounting shoes on lasts comprising means for supporting a two-part last in broken condition with the forepart of a shoe loosely mounted on the forepart of the last, a shoe horn, means for operating said shoe horn to draw the heel portion of the shoe over the heel portion of the last, such operation of the horn serving to assist the operator in straightening the last, a wedge movable into position between the fore and rear sections of the last to hold the last in straightened condition, and friction means operable upon the shoe bottom to urge the shoe rearwardly upon the straightened last.
